TIMING DEVICE

Harry Powell, Philadelphia, Pa.

Application June 5, 1935, Serial No. 25,109

8 Claims. (Cl. 200—36)

This invention relates to timing devices designed for governing the operation of various kinds of apparatus, particularly radio receivers and the like.

5 Broadly considered, my invention is directed toward the provision of a simple and reliable means operated by a clock movement and capable of being set to cause the apparatus to begin functioning at any desired predeterminable hour 10 and to continue functioning for any desired predeterminable period. When embodied in a suitable form such as herein disclosed, by way of example, for controlling radio receivers, the timing device of my invention can be set for reception 15 of broadcasts beginning at any hour and lasting say for fifteen, thirty, forty-five and sixty minute periods.

Another object of my invention is to provide in connection with the timing device having an auxiliary hand for coordination with the dial of the clock movement and time switch means to control an electric circuit, a single element whereby said auxiliary hand may be set to indicate the time of starting of the governed apparatus and 25 whereby the switch means may be selectively set to predetermine the duration of the operation of the apparatus.

Other objects and attendant advantages of this invention will be manifest from the detailed 30 description following of the drawings, wherein Fig. I shows the front elevation of a timing device conveniently embodying the present improvements, in a form suitable for automatically controlling the operation of radio receivers and 35 the like.

Fig. II shows the rear elevation of the device.

Fig. III is a view with the front of the casing of the device removed to show the mechanism at the interior.

40 Fig. IV is a fragmentary view taken as indicated by the arrows IV—IV in Figs. I and III.

Fig. V is a detail view of one of the time switch elements embodied in the mechanism.

Fig. VI is a fragmentary detail plan viewed as 45 indicated by the arrows VI—VI in Figs. III and IV; and

Fig. VII is a view on a larger scale corresponding to Fig. IV and showing diagrammatically the electric circuit of the timing device.

50 As herein delineated, my improved timing device comprises a casing 1 which is preferably of rectangular configuration and formed from bakelite or other dielectric material. Housed within the casing 1 is a clock movement 2 which, except 55 as hereinafter noted, may be of conventional con-

struction, said movement having a minute hand shaft 3, and an hour hand sleeve 4 rotating independently about said shaft. Both the shaft 3 and the sleeve 4 extend outward through an opening 5 in the front wall 6 of the casing 1 for attachment respectively of the minute and hour hands 7 and 8 (Figs. I, IV and VII) which overtravel a dial 9 on said front wall. The illustrated clock movement is of the spring actuated type adapted to be wound by means of a key 10 (Fig. II) which is 10 accessible at the back of the casing 1, there being also, as ordinarily, a knob 11 for setting the clock hands 7 and 8.

5 In addition to the hands 7 and 8 there is provided, in accordance with my invention, an auxiliary hand 12 on still another sleeve 13 which, in turn, is independently rotatable about the hour hand sleeve 4. Secured to the inner end of the sleeve 13 within the casing 1 is a disk 14 of insulating material which forms a part of the 15 rotary time switch means, said disk having four spaced inset concentric rings 15, 16, 17 and 18 on one face thereof. Fast on the sleeve 13 immediately forward of the disk 14 is a miter gear pinion 19 whereewith a similar pinion 20 on the 20 lower end of a stem 21 is adapted to mesh, said stem being frictionally engaged in a bearing 25 sleeve 22 secured in the top wall 23 (Fig. III) of the casing 1 by means of a clamp nut 24 which opposes a head 25 at the top of said sleeve. At 30 its upper protruding end, the stem 21 has a finger knob 26 whereby it may be axially shifted as well as rotated for purposes later on explained. From Figs. III, IV and VII it will be observed that the hub of the pinion 20 at the lower end of the 35 stem 21 is formed with a circumferential groove 27 for engagement by a laterally-projecting tongue 28 on a vertical slide 29 which is slotted 40 at its opposite ends for guidance by headed studs 30 secured in the front plate 31 of the clock movement 2. As further shown in Figs. III, IV, VI and VII, the slide 29 carries a current-carrying brush 32 which bears against the front face of the disk 14, and which, by axial movement of the stem 21, is shifted radially of said disk so that it 45 can be brought into contact with any one of the rings 15—18.

Fast on the hour hand sleeve 4 adjacent the disk 14 is another disk 33 of dielectric material which constitutes another part of the rotary 50 time switch and which has an inset metallic sector 34 on its frontal face (see Figs. IV, V and VII). As shown, one side edge of the sector 34 is straight, while the other side edge is stepped, with resultant formation of portions 35, 36, 37 55

and 38 of different circumferential widths respectively in line with the rings 15-18 on the disk 14 and respectively corresponding in this instance to fifteen, thirty, forty-five and sixty minute periods. During rotation of the disk 33, the sector 34 wipes against radially-aligned spring brush contacts 39, 40, 41 and 42 respectively extending from the rings 15-18 of the disk 14 at radial distances corresponding to the allocation of the portions 35-38 of the sector 34. As shown, the sector 34 is integral or continuous with a concentric ring 43 on the hub of the disk 33 upon which a current-carrying brush 44 bears, said brush being supported, with interpolation of suitable insulation (not illustrated), by a screw 45 on the front plate 31 of the clock movement.

Associated with my timing device is an electric cord 46 which enters the back of the casing 1 through a bushing 47, see Fig. II, and which, at its free end, is fitted with a plug 48 for insertion into a socket (not shown) of an electric power line. Set into the back of the casing 1 (Fig. II) at one of the top corners, is a conventional form 25 of a manually-operable cutout switch 49 having a toggle lever 50 to actuate a swingable spring-influenced circuit closing member 51 whereof the ends overreach terminal studs 52 and 53 fixed in a dielectric supporting disk 54. The timing device is further fitted with a double plug receptacle 55 whereof the heads 56 and 57 project outward through conformative openings in the back of the casing 1. One of the two heads 56 and 57 of the receptacle 55 is intended to be 35 used for connection of a radio receiver or other apparatus which is to be governed, while the other head may be used for connection of an electric lamp or the like. As shown in Figs. III and VII, the lead 46a of the cord 46 extends to 40 the circuit closing member 51 of the toggle switch 49, and the other lead 46b to corresponding sides of the two receptacle heads 56 and 57, the other corresponding sides of said receptacle heads being connected, by a conductor 58, with 45 the brush and the fixed contact stud 52 of the cutout switch 49. Still another conductor 59 connects the brush 32 with the fixed contact 53 of the cutout switch 49.

The operation of my timing device is as follows: If it is desired to have the radio receiver or other governed apparatus function automatically, say for a period of an hour beginning at 12 o'clock, the lever 50 of the cutout switch is thrown to bring the circuit closing member 51 into engagement with the contact stud 53 of said switch. With this accomplished, the rod 21 is axially depressed in the bearing sleeve 22 until the miter gear wheel 20 at the lower end thereof meshes with the miter gear 19 as shown, 55 whereupon said stem is turned to bring the auxiliary hand 12 into line with the numeral twelve on the dial 9, also as shown. When the stem 21 is positioned as just explained, the brush 32 on the slide 29 bears upon the ring 18 of the disk 14. Incident to rotation of the sleeve 18, the radially-aligned brush contacts 39, 40, 41 and 42 of the disk 14 are brought to such position that the metallic sector 34 on the disk 33 will begin to make contact therewith at the 60 instant when the hour hand points to the numeral twelve on the dial 9. This contact is maintained for a period of sixty minutes while the portion 38 of the sector 34 wipes past the brush contact 42 of the ring 18 of the disk 14 upon 65 which the brush 32 is set. During the described 70 instant the brush 32 is set. During the described 75

interval, electric current will flow from the supply source through the lead 46a of the cord 46, the circuit closing member 51 of the cutout switch 49, the contact stud 53, the conductor 58, the brush 32, and from thence through the ring 18 of the disk 14, the brush contact 42, the sector 34 of the disk 33, the brush 44, the conductor 58, the receptacle head 56 and the return lead 46b of said cord 46 to operate the radio receiver. At the same time, current will flow through the socket head 57 to illuminate the lamp connected thereto. If, by way of further illustration, it is desired to have the radio receiver function for fifteen minutes instead of an hour, the stem 21 is raised after setting of the auxiliary hand 12 until the brush 32 bears upon the ring 15 of the disk 14 as shown in dot and dash lines in Fig. IV whereupon the narrower upper portion 35 of the sector 34 will wipe the brush contact 39 during rotation of the disk 33 under the drive of the clock movement 2. Similarly, by shifting the stem 21 so that the brush 32 engages either the rings 16 or 17 on the disk 14, the radio receiver may be caused to function for thirty or forty-five minute periods. To aid setting of the stem 21, the latter is provided with suitably spaced graduations as shown in Figs. I and II.

When the cutout switch 49 is thrown to bring its closure member 51 into engagement with the contact stud 32, it will be apparent from Fig. VII that the electric current will pass directly from the supply line through the receptacle 55 with the timing device eliminated from the circuit.

Having thus described my invention, I claim: 35

1. A time switch comprising a rotating metallic sector connected to one side of an electric circuit; a number of stationary juxtaposed radially-separated metallic rings concentric with the axis of the sector and insulated therefrom; 40 radially-aligned brush contacts, one extending from each of said rings and adapted to wipe the sector; and a brush connected to the other side of the electric circuit and shiftable radially of the sector axis into contact with any selected 45 one of the rings.

2. A time switch comprising a pair of relatively-rotating juxtaposed coaxial disks of insulation; an inset metallic sector in one face of one of said disks connected to one side of an 50 electric circuit; a number of radially-separated inset concentric metallic rings on the contiguous face of the other of the disks; radially-aligned brush contacts, one projecting from each of said rings into wiping engagement with the face of 55 the sector carrying disk; and a brush connected to the other side of the circuit and shiftable radially of the face of the ring-carrying disk into contact with any selected one of the rings.

3. A time switch comprising a disk of insulation with an inset metallic sector on one face connected to one side of an electric circuit; a clock movement for rotating the disk; a normally-stationary coaxial rotatively-adjustable juxtaposed disk of insulation with a number of 60 inset radially separated concentric metallic rings on its contiguous face; a series of radially-aligned brush contacts, one extending from each of the rings into engagement with the face of the rotating disk; and a brush connected to the 65 other side of the electric circuit and adjustable radially of the normally stationary disk for selective contact with the metallic rings.

4. A time switch comprising a clock movement with minute and hour hands, and with an auxil- 75

- 5 iary hand settable independently of said minute and hour hands; a disk of insulation rotating with one of the clock hands and having an inset metallic sector on one of its faces; a juxtaposed normally stationary disk of insulation fixed in relation to the auxiliary hand and having a number of radially-separated inset concentric metallic rings on its contiguous face; a series of radially-aligned brush contacts, one extending from each of the metallic rings and bearing on the face of the sector disk; and a current-carrying brush connected to the other side of the circuit and shiftable radially of the ring disk into contact with any selected ring of said disk.

10 5. A time switch comprising a clock movement with a shaft carrying a minute hand, a sleeve independently rotatable about said shaft and carrying an hour hand, another sleeve independently rotatable about the hour hand sleeve and carrying an auxiliary hand, and means whereby the auxiliary hand may be set independently of the clock hands; a disk of insulation secured to the hour hand sleeve and having an inset metallic sector on one of its faces connected to one side of an electric circuit; a juxtaposed disk of insulation secured to the auxiliary hand sleeve and having a series of radially-separated concentric inset metallic rings on its contiguous face; a series of radially-aligned brush contacts, one extending from each of the rings into engagement with the sector face of the sector disk; and a brush connected to the other side of the electric circuit and shiftable radially of the ring carrying face of the ring disk into contact with any one of the rings.

15 6. A time switch in accordance with claim 5, wherein the sector has zones in line with the rings of a width corresponding respectively to fifteen, thirty, forty-five and sixty minute periods.

20 7. A time switch comprising a clock movement with an enclosing casing, minute and hour hands coordinating with a dial at the front of said casing, and an auxiliary hand coordinating with a dial and settable independently of the minute and hour hands; a disk of insulation within the casing rotating with one of the clock

25 5 hands and having an inset metallic sector on one of the faces connected to one side of an electric circuit; a juxtaposed coaxial disk of insulation within the casing movable with the auxiliary hand and having a number of inset radially-separated metallic rings on its contiguous face, a series of radially-aligned brush contacts, one extending from each of the metallic rings of the ring disk into engagement with the sector face of the sector disk; a brush connected to the other side of the circuit and shiftable radially of the ring disk into contact with any selected one of the rings on said disk; and means accessible at the exterior of the casing for shifting the last mentioned brush as aforesaid.

30 8. A time switch comprising a clock movement with an enclosing casing, a shaft carrying a minute hand, a sleeve independently rotatable about said shaft and carrying an hour hand, another sleeve independently rotatable about the hour hand sleeve and carrying an auxiliary hand, a disk on the front face of the casing for coordination with the several hands; a disk of insulation secured to the hour hand sleeve within the casing and having an inset metallic sector on one of its faces connected to one side of an electric circuit; a juxtaposed disk of insulation secured to the auxiliary hand sleeve within the casing and having a series of radially-separated concentric inset metallic rings on its contiguous faces, a radially-aligned series of brush contacts, one extending from each of the rings of the ring disk and bearing against the sector face of the sector disk; a brush connected to the other side of the electric circuit and wiping the ring carrying face of the ring disk; means for setting the auxiliary hand and for moving the brush radially of the ring disk into contact with any selected ring of said disk embodying a stem axially shiftable and rotatable in a bearing in a wall of the casing, said stem having a manipulating knob at the top and a bevel gear at the bottom capable of being meshed with a bevel gear on the auxiliary hand sleeve and a guide member shifted by axial movement of the stem and carrying said last mentioned brush.

35 9. A time switch comprising a clock movement with an enclosing casing, minute and hour hands coordinating with a dial at the front of said casing, and an auxiliary hand coordinating with a dial and settable independently of the minute and hour hands; a disk of insulation within the casing rotating with one of the clock

40 10 hands and having an inset metallic sector on one of the faces connected to one side of an electric circuit; a juxtaposed coaxial disk of insulation within the casing movable with the auxiliary hand and having a number of inset radially-separated metallic rings on its contiguous face, a series of radially-aligned brush contacts, one extending from each of the metallic rings of the ring disk into engagement with the sector face of the sector disk; a brush connected to the other side of the circuit and shiftable radially of the ring disk into contact with any selected one of the rings on said disk; and means accessible at the exterior of the casing for shifting the last mentioned brush as aforesaid.

45 11. A time switch comprising a clock movement with an enclosing casing, a shaft carrying a minute hand, a sleeve independently rotatable about said shaft and carrying an hour hand, another sleeve independently rotatable about the hour hand sleeve and carrying an auxiliary hand, a disk on the front face of the casing for coordination with the several hands; a disk of insulation secured to the hour hand sleeve within the casing and having an inset metallic sector on one of its faces connected to one side of an electric circuit; a juxtaposed disk of insulation secured to the auxiliary hand sleeve within the casing and having a series of radially-separated concentric inset metallic rings on its contiguous faces, a radially-aligned series of brush contacts, one extending from each of the rings of the ring disk and bearing against the sector face of the sector disk; a brush connected to the other side of the electric circuit and wiping the ring carrying face of the ring disk; means for setting the auxiliary hand and for moving the brush radially of the ring disk into contact with any selected ring of said disk embodying a stem axially shiftable and rotatable in a bearing in a wall of the casing, said stem having a manipulating knob at the top and a bevel gear at the bottom capable of being meshed with a bevel gear on the auxiliary hand sleeve and a guide member shifted by axial movement of the stem and carrying said last mentioned brush.

HARRY POWELL.
